(57) **CLAIM**

The ornamental design for a safe, as shown and described.

DESCRIPTION

FIG. 1 is a front and top perspective view of a safe, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, showing the safe in an open position;

FIG. 10 is an enlarged view of a portion labeled “FIG. 10” in FIG. 1; and,

FIG. 11 is an enlarged view of a portion labeled “FIG. 11” in FIG. 3.

The dashed broken lines in the figures illustrate portions of the article that form no part of the claimed design. The dot-dash-dot lines in FIGS. 1, 3, 10 and 11 represent cutting lines of enlarged views and form no part of the claimed design.
